UNITED STATES PATENT OFFICE.

JOSEPH E. JOHNSON, JR., OF HARTSDALE, NEW YORK.

REISCH

PROCESS OF PRODUCING FERRO-SILICON OF HIGH SILICON CONTENT IN BLAST-FURNACES.

1,231,260.

Specification of Letters Patent. Patented June 26, 1917.

No Drawing.

Application filed June 20, 1916. Serial No. 104,779.

To all whom it may concern:

Be it known that I, JOSEPH E. JOHNSON, Jr., a citizen of the United States, residing at Hartsdale, in the county of Westchester 5 and State of New York, have invented certain new and useful Improvements in Processes of Producing Ferro-Silicon of High Silicon Content in Blast-Furnaces, of which the following is a specification.

10 This invention relates to a process of smelting ores in the blast furnace, and aims to produce in an economical manner, ferro-silicon containing a high percentage of silicon.

15 There are at present in common use two varieties of commercial ferro-silicon, one produced in the blast furnace, and the other produced in the electric furnace. The first variety, while comparatively inexpensive to 20 produce, is low in its percentage of silicon, and the second variety while very high in silicon content, commonly 50% or more, is expensive to produce on account of the high electric current consumption.

25 It is the object of my invention to produce in the blast furnace, ferro-silicon containing a high percentage of silicon, thereby securing the advantage of the electric furnace in respect to the high silicon content, 30 and the advantage of the blast furnace with respect to economy of production.

With this object in view, my invention consists of an improved method of smelting, in which a blast is employed, rich in 35 oxygen, whereby the temperature of combustion is increased to such degree that the silica will be reduced on a scale which will produce ferro-silicon containing a high percentage of silicon and equaling the product 40 commonly produced in the electric furnace.

In carrying my improved method into effect, I make use of a form of blast furnace, in a general way similar to that now 45 universally employed for smelting ores, and I charge the same with ore and fuel in the usual and well known manner. I introduce at the base of the charge, through the usual tuyers, a blast which is rich in oxygen 50 as compared with the usual blast of atmospheric air, the result of which is the production of a much higher combustion temperature than is available in the furnace as ordinarily operated, and a correspond-

ingly increased reduction of the silica. The 55 reactions in this operation may be expressed by the following formula:

Where atmospheric air is employed in the 60 blast there is about $3\frac{1}{2}$ times more by weight of nitrogen than there is of oxygen, and since, other things being equal, the temperature obtainable is inversely proportional to the weight of the products of combustion, 65 the temperature produced is only about $\frac{1}{3}$ as high as would be produced by a blast of pure oxygen. In other words, the nitrogen in such large proportions in the blast acts as a dead weight on the combustion and 70 keeps the temperature down to such point that the reduction of silica is confined to limits in which the final product contains a comparatively small per cent. of silicon, rarely above 16%. 75

By my invention, by employing a blast rich in oxygen the increased temperature of combustion is very marked, and if pure oxygen were employed the gain would be so enormous that it would greatly exceed the 80 requirements for the end in view, and since the increase of temperature need be only about $\frac{1}{3}$ higher than is now obtainable with the use of atmospheric air, I find it sufficient for my purpose to employ a blast in which 85 the oxygen and nitrogen will be of equal weights, or in approximately that proportion. A mixture of this character is more economically produced commercially than pure oxygen, and such mixture is sufficiently 90 rich in oxygen to obtain the temperature required, for the reduction of the silica on the desired increased scale, and for the creation of the amount of heat available at that 95 temperature to bring about such reduction. 95

Ferro-silicon as most generally employed in metallurgy, contains about equal proportions of iron and silicon in order to enable it to combine under the most favorable conditions with the molten metal in which it is 100 to be incorporated. A blast in which the nitrogen and oxygen are mixed in equal or substantially equal proportions I have found admirably adapted for producing that temperature of combustion which will bring 105 about the reduction of the silica and iron in the proportions mentioned, and a blast mixture of this character may be economi-

cally and conveniently produced and with a far smaller plant than is required for a richer mixture or for pure oxygen.

Having thus described my invention, what 5 I claim is:

1. The process of producing ferro-silicon of high silicon content in a blast furnace, which consists in charging the furnace with ore and fuel, and supplying a blast 10 rich in oxygen to reduce the silica on a scale to produce ferro-silicon containing a high percentage of silicon.

2. The process of producing ferro-silicon of substantially 50% silicon in a blast furnace, which consists in charging the furnace with ore and fuel, and supplying a blast containing equal or substantially equal parts by weight of oxygen and nitrogen to reduce the silica on a scale to produce a ferro-silicon containing a high percentage 20 of silica.

In testimony whereof, I have affixed my signature.

JOSEPH E. JOHNSON, JR.
